UNITED STATES PATENT OFFICE

98,941

DESIGN FOR A HOLDER FOR KEYS OR SIMILAR ARTICLE

Edwin Ernest Jessee, Houston, Tex.

Application August 1, 1935, Serial No. 57,909

Term of patent 3½ years

To all whom it may concern:

Be it known that I, Edwin Ernest Jessee, a citizen of the United States, residing at Houston, in the county of Harris and State of Texas, have invented a new, original, and ornamental Design for a holder for Keys or Similar Article, of which the following is a specification, reference being had to the accompanying drawing, forming part thereof.

The opposite sides of these three figures are identical with those shown.

I claim:—

The ornamental design for a holder for keys or similar article, as shown and described.

EDWIN ERNEST JESSEE.
